UNITED STATES PATENT OFFICE.

ADOLPH RUTLER, OF SUNBURY, PENNSYLVANIA, ASSIGNOR TO SUSQUEHANNA SILK MILLS, OF SUNBURY, PENNSYLVANIA, A CORPORATION OF PENNSYLVANIA.

PROCESS OF DYEING FABRICS.

1,005,888.

Specification of Letters Patent. Patented Oct. 17, 1911.

Application filed November 16, 1909. Serial No. 528,377.

To all whom it may concern:

Be it known that I, ADOLPH RUTLER, a citizen of the United States, and a resident of Sunbury, county of Northumberland, State of Pennsylvania, have invented a certain new and useful Process of Dyeing Fabrics, of which the following is a specification.

This invention relates to processes of dyeing fabrics of silk, cotton or other material in large quantities; and the object of the invention is to provide a process of economically and uniformly dyeing large quantities of fabric in a short period of time.

For the accomplishment of the above object and for such other purposes as will hereinafter appear, the invention comprises the process of dyeing a fabric which process comprises passing the fabric in a web, wetting the fabric with free flowing jets of dye stuff supplied in excess of what the fabric will absorb, thus dyeing the same, the excess of dye stuff being permitted to run off of the fabric into a bath with which it is permitted to mix so as to keep the bath of uniform strength and to be again used in wetting the fabric.

Suitable means for carrying out the above process comprise, a dyeing tub for holding a bath of dyeing liquid, rollers for winding and unwinding said fabric, and means for transferring a portion of the dye liquid from said tub to the fabric between the rollers, the excess of the dye liquid for wetting the fabric being permitted to return to the dyeing bath in the tub and mixed therewith so as to keep the bath uniform and to be again used in wetting the fabric.

Referring to the drawings: Figure 1 is a vertical section through my improved apparatus by means of which my process may be practiced. Fig. 2 is a side elevation of the apparatus, the tank being in cross-section. Fig. 3 is a plan of the apparatus. Fig. 4 is a detail of the clutch partly in section.

In the drawings 1 designates a basin or dyeing tub in which there is contained a dye bath 2. Near the upper edge of the tub are suitably secured three rollers numbered respectively, 3, 4 and 5, all of which are supported in suitable bearings secured to the sides of the tub. The rollers 3 and 5 are preferably placed near the sides of the tub, whereas the roller 4 is preferably placed in the center between the rollers 3 and 5, as shown in Fig. 1. At one edge of the tub

above the roller 3 is provided a supply roll 7 of fabric to be dyed, said roll being supported upon suitable standards 8 secured to the sides of the tub. The fabric from the roll 7 is passed down under the roller 3, then over the roller 4 and under the roller 5 to form a web 9, thence passing to a delivery roll 10 which is mounted on standards 11 on the sides of the tub opposite the standards 8 which support the supply roll 7. At one end of the delivery roll 10 is rotatably mounted one end of a short shaft 11' to the other end of which is secured a beveled gear 12 which is adapted to mesh with another beveled gear 13 secured to a driving shaft 14. The short shaft 11 is provided with a spline 15 upon which is slidably mounted a clutch 16 which is in the form of a sleeve and provided at one edge with notches 17 which are adapted to engage corresponding notches on the end of the delivery roll 10, the clutch being arranged to be moved into and out of engagement with the delivery roll 10 by shifting the clutch 16 back and forth upon the splined shaft 11. The supply roll 7 is also provided at one end with a clutch mechanism similar to that already described for the delivery roll 10, and the parts for that reason are given the same reference numerals. It is to be noted however, that the beveled gear 18 is arranged on the right side of the bevel gear 12 with which it is in mesh, whereas the beveled gear 13 is arranged on the left side of the bevel gear 12 with which it is in mesh, so as to drive the rolls 7 and 10 in opposite directions. As it is only necessary to drive one of the rolls at a time, each of the clutches 16 is connected to a shifting bar 19 which is provided with suitable pins 20 each of which engages a suitable slot 21 in the clutch 16, as shown in the detail view of the clutch, Fig. 4. The shifting bar 19 is preferably pivoted at its center upon the pin 22 secured to the bracket 23 so that only one of the rolls can be driven at a time, it being possible to set the shifting bar 19 in an intermediate position so that both of the clutches are out of engagement with the ends of the rolls.

From the above it will be seen that the fabric can be wound upon the delivery roll 10 by setting the shifting lever 19 as shown in Fig. 3, and when it is desired to rewind the fabric upon the roll 7 the lever 19 is

shifted so that clutch 16 on the roll 10 is released and the clutch 16 on the roll 7 comes into position to rewind the fabric upon the roll 7.

5 The driving shaft 14 may be driven in any desired manner the same being usually driven always in the same direction.

10 Immediately over the roller 4 is provided a wetting device, which in the present instance, consists of a receiving tank 30 which is supplied continuously with the dye stuff obtained from the bath 2 through the pipes 31 and 32 by means of the centrifugal pump 33 which is driven by the shaft 14 through 15 the medium of the gears 34 and 35, a suitable clutch 36 operated by means of a handle 37 being provided for shifting the clutch 36 into and out of engagement with the gear 35 which normally runs loosely upon the 20 pump shaft 38. The lower end of the receiving tank 30 terminates in a pipe 39 the lower end of which connects with two branch pipes 40 and 41 which extend across the tank above the web. These pipes are 25 provided with a series of perforations 42, on their under sides, through which the dye liquid is permitted to flow in continuous jets upon the web 9 of the fabric as the same is being wound upon the roll 10, the web passing 30 under the face of the roller 5, where it is subjected to considerable pressure on account of the tension existing in the web. This pressure acts to diffuse the dye through the fibers of the web, tending to make the 35 dyeing effect quite uniform. The tension in the web is maintained by means of set screws 45 and 46, the set screws 45 being tightened when it is desired to wind the fabric upon the roll 10, the same being relaxed and the 40 set screws 46 tightened when it is desired to wind the fabric upon the roll 7. The tension of the web is maintained uniform by means of tension devices 50 and 51, two of which are mounted at each side of the tank. 45 Each of the tension devices comprises a fixed guide bracket 53 having a sliding block 54 with a guide stem 55 sliding through the ends of the bracket, and about each stem is a spring 56 which tends to force the block 50 outward. The blocks 54 are connected by rotatable tension rods 57 as shown in Fig. 3. These devices maintain the web taut as it passes between the rolls as will be readily understood. The tension rods also tend to 55 keep the web smooth and prevent it from becoming wrinkled or folded, particularly at the edges.

The operation is as follows: The shaft 14 being rotated, the web 9 is advanced from 60 one roll to the other while the pump is actuated, so as to raise the dye from the bath. The liquid dye then flows along the pipes 40 and 41 and falls continuously upon the passing web. The movement of the 65 pump is regulated so that an excessive

amount of dye is allowed to run upon the passing web, in other words more dye is allowed to run upon the passing web than can possibly be absorbed by the same, the excess of dye being permitted to run off of 70 the web into the bath, it being important that the web should not pass through the bath or the fabric immersed therein, and for this reason the rollers 3, 4 and 5 are situated above the level of the bath in the 75 tank. The dye which is taken up by the fabric diffuses itself in passing under the roller 5 and penetrates into the interior of all the strands of the fabric. The web is passed back and forth several times, the 80 reversal of the driving roll being accomplished by simply operating the shifting lever 19 as before described, the web being wet by the dye from the pipes 40 and 41 at each passage. It is necessary that the fabric 85 should be passed through the jets of dye an even number of times, at least twice, and ordinarily about ten times, to get the required shade of color, for the reason that if the fabric was passed only once through 90 the dye jets, the first part of the fabric passed through the dye jet would be moved relatively slow and would absorb a relatively large amount of dye, but as the fabric is wound upon the roll 10 and as the same 95 increases in diameter, the speed of the fabric under the dye jets also increases so that the fabric is dyed uniformly less and less toward the end of the fabric. This difficulty is overcome by reversing the movement of 100 the fabric and rewinding the same upon the roll 7. In passing in the opposite direction from that described, the roller 3 will produce a diffusing pressure on the web as it passes.

By the above described process it will be 105 seen that the fabric is dyed by withdrawing liquid dye from a bath of same, and pouring it in a uniform manner upon the fabric, which is passed in a web, the liquid dye withdrawn from the bath being poured 110 upon the web in an excessive amount, the excess of the liquid used in wetting the fabric being returned to the main body of dye in said bath and mixed therewith so as to keep the dye in said bath of substantially 115 uniform strength at all times by the continuous circulation and mixing of the dye. The excess dye, being in large excess, flows over the edges of the cloth, there being merely a film left. This film is pressed into 120 and through the cloth by rollers 3 and 5 to thoroughly saturate the same. It is also to be noted that the main portion of the excess dye poured upon the fabric returns to the original bath substantially unchanged, from its original condition whereas, the excess dye which is weakened by contact with the fabric is mixed with the main body of the dye bath which is of substantial size to compensate for the weakening of small quanti- 125 130

ties of the dye liquid. Due to the continuous circulation and mixing of the dye liquid it makes it possible to add new dye liquid to the bath from time to time to compensate 5 for the dye liquid retained by the fabric and to strengthen the dye as it becomes weak. It will be noticed that the fabric spans the bath of dye, or is stretched in a web over the same under tension so that the pores of the 10 material are opened to receive the dye as the spanning web is reeled from one roll to the other.

If fabric could be dyed by always using new dye liquid the dyeing of fabric would 15 be comparatively easy, but this method is so expensive that means must be provided for using the same dye liquid over and over again. In order to do this it is necessary that the bath of dye liquid should always be 20 of uniform strength and not one part of the bath stronger or weaker than another, and it is for this reason that the dye in the above described process, is poured on the web in an excessive amount and then returned to 25 the dye bath and mixed therewith so as to make the bath of uniform strength before it is used over again. This continuous circulation of the dye liquid, by always pouring an excessive amount upon the web 30 insures that the web shall always receive a uniform quality of the dye, so as not to cause streaks or uneven dyed places to appear upon the finished fabric.

The above method of applying the dye in 35 excess, and then returning the same to the original bath, which is of substantial size to easily compensate for any weakened dye liquid, is far superior to passing the fabric through the dye bath itself which is never 40 of uniform strength, or in atomizing or spraying the liquid dye upon the fabric which is likewise not successful, as the dye sprayed or atomized upon the fabric is such a small amount that the dye is never uni- 45 form and the method is likewise hampered by being so exceedingly slow and tedious as to be very expensive without good results.

In the apparatus for carrying out the above process it will be seen that the fabric 50 to be dyed passes over the roller 4 and under the rollers 3 and 5 so as to give an inclined surface to the fabric so that the dye liquid which is poured upon the fabric from above the roller 4 will be uniformly distributed over the fabric and the excess will 55 readily run off and return to the bath in a uniform manner. The fabric is also kept taut as above described, so as to prevent the fabric from sagging or wrinkling, which 60 further facilitates the dye liquid being uni-

formly distributed upon the fabric and allowing the excess to readily return to the bath.

Near the bottom of the tank oppositely disposed guide rollers 60 and 61 are provided, which are disposed substantially beneath the rollers 3 and 5. Above the rollers 60 and 61 are arranged guide rollers 62 and 63 as shown. These lower rollers are for the purpose of guiding the web of fabric 70 through the tank in order to enable the fabric to be washed in a suitable cleansing bath. It is to be distinctly understood, however, that these rollers are not to be used in the dyeing process. 75

While the invention has been described with particular reference to the details of construction and operation, it is not to be understood as limited thereto, as many changes may be made and still fall within 80 the scope of the following claims.

What I claim is:—

1. The process of dyeing materials from a bath of dye which comprises passing said material in a web over said bath and wholly 85 out of contact therewith, showering dye upon such web of material in excess of that which it can absorb, and allowing said excess to flow freely from said web into the bath to be reused. 90

2. The process of dyeing materials which comprises showering dye upon a span of such material from a bath while the same is moved under tension directly over said bath, and allowing said dye to flow freely 95 from said span directly into said bath for reuse.

3. The process of dyeing fabric which comprises passing the same in an arc over a bath of dye under tension, showering dye 100 from said bath in excess upon said arc, and allowing said excess to flow freely from said arc directly into said bath for continued use in dyeing said fabric.

4. The process of dyeing fabrics which comprises withdrawing dye from a bath, pouring said dye in excess upon the fabric to be dyed, passing said fabric in a web out of contact with said bath and allowing said excess dye to flow freely from said web into 110 the bath to be mixed therewith for use in dyeing the fabric.

In testimony whereof I have signed this specification in the presence of two subscribing witnesses.

ADOLPH RUTLER.
